RAYMOND G. MOORE AND ARTHUR CLAUD-MANTLE, OF BRIDGEPORT, CONNECTICUT,
ASSIGNORS TO THE BASSICK COMPANY, OF BRIDGEPORT, CONNECTICUT, A COR-
PORATION OF CONNECTICUT

LATCH

Application filed July 8, 1927. Serial No. 204,340.

The present invention relates to latches, and particularly a type adapted for use with kitchen cabinets, or the like, and has for an object to provide a latch of this character which may be formed from sheet metal, and which will be very simple and inexpensive in construction and assembly, and efficient and reliable in operation.

It is particularly proposed to provide a latch having a spring actuated latch bolt, and a spring actuated operating handle adapted to have rocking movement in either one of two directions to actuate the bolt, and which is further adapted to be yieldably retained in its normal position independent of the position of the latch bolt, so that it will not drop from such position when the bolt is not fully projected.

It is further proposed to provide a latch construction in which the latch bolt and the operating handle are compactly super-imposed upon each other within the casing in such manner that the complete latch will be relatively thin and flat in appearance.

A further object is to provide a latch of symmetrical form, and which may be used with equal facility on either a right or left hand door.

With the above and other objects in view an embodiment of the invention is shown in the accompanying drawings, and this embodiment will be hereinafter more fully described with reference thereto and the invention will be finally pointed out in the claims.

In the drawings:

Fig. 1 is a plan elevation of a latch, according to the present embodiment of the invention.

Fig. 2 is a bottom plan view thereof.

Fig. 3 is a side elevation.

Fig. 4 is a rear elevation.

Fig. 5 is a longitudinal sectional view taken along the line 5-5 of Fig. 1.

Fig. 6 is a bottom plan view showing, in full lines, the position of the latch bolt with the operating handle in the retracted position, the operating handle being moved downwardly, and showing, in dotted lines, the position of the operating handle when the

same is moved upwardly to retract the latch bolt.

Fig. 7 is a perspective view of the casing.

Fig. 8 is a perspective view of the latch bolt.

Fig. 9 is a perspective view of the operating handle.

Fig. 10 is a perspective view of the handle actuating spring and its supporting plate.

Similar reference characters indicate corresponding parts throughout the several figures of the drawings.

Referring to the drawings, the latch, according to the embodiment shown therein, comprises a flanged sheet metal case 20 of vertically elongated shape, raised in spaced relation to the ends, as at 21, and provided in each of the end portions with holes 22 for engagement of attaching screws. In the forward side flange of the casing there is provided a slot 23 for the latch bolt, and in the rearward side flange there is provided a slot opening including a portion 24 in alignment with the slot 23 and also adapted to receive the latch bolt, and a slot portion 25 above the portion 24 and extended at each end with relation thereto and adapted to receive and permit rocking movement of the latch bolt operating handle, as will hereinafter more fully appear. In one of the end flanges a prong 26 is punched inwardly and serves to retain the latch bolt spring, hereinafter referred to.

The latch bolt operating handle member comprises a handle portion 27 pressed into curved shape and rounded in cross section, and a flat portion 28 extended through the slot 25 and disposed within the latch casing. The portion 28 is provided at its forward edge with spaced rocking points 29, 30, preferably rounded as shown, and adapted to engage the inner surface of the forward flange of the casing above and below the latch bolt slot 23.

Bosses 31, 32 are pressed from the surface of the portion 28 in relation to the rocking points and are adapted to bear upon portions of the latch bolt member hereinafter referred to. For the purpose of yieldably retaining the handle in its normal position, and with both rocking points in engagement with

the forward flange of the casing, a spring 33 is provided, this spring being secured at one end in a thin metal plate 34 by flanging over the said plate, as at 35, being bent upwardly 5 at its other end, as at 36, and extended through the opening 37 in the plate, and engaged with the perforation 38 provided medially of the portion 28 of the handle member. The plate 34 corresponds to the shape 10 of the recess formed at the inner side of the casing by the raised portion 21, and is set in this recess, thereby protecting and retaining the spring and providing a flat bearing surface upon which the handle member 15 may operate.

The latch bolt comprises a flat rectangular strip of sheet metal 40, of relatively heavy gauge, bevelled at its nose end as at 41, and provided at its upper and lower edges with 20 oppositely disposed aligned projecting lugs or fingers 42, 43, one of these fingers being provided with a perforation 44 for engagement therewith of the bolt actuating spring, hereinafter referred to. The latch bolt is 25 slidably engaged in the slots 23, 24, with the lugs 42, 43 engaged with the bosses 31, 32, of the latch operating handle, and is yieldably held in projected position, and against said bosses, by means of a hairpin spring 45 30 held within the casing by engagement of one of its end portions, bent as at 46, with the flange of the casing, and having its curved portion inserted and held beneath the prong 26 of the casing, its other end portion being 35 bent, as at 47, into the perforation 44 provided in the latch bolt.

The latch bolt is of such dimensions that it may be readily assembled with the casing by hand, and for this purpose the distance 40 from the nose end 41 to the rearward edges of the lugs 42, 43 is slightly less than the interior width of the casing, so that by first engaging the tail end in the slot 24 to a point where the lugs abut the casing, the nose end 45 may be inserted in the slot 23, the spring 45 bringing the same into the projected position with the lugs abutting the bosses 31, 32 of the handle member and thereby limiting the projection of the bolt.

50 As shown in Fig. 5, the latch bolt is adapted to engage a suitable keeper 48 provided with a bevelled strike portion 49 adapted, as the door is closing, to press the bolt inwardly to the point where it enters beneath 55 the keeper. During the pressing in of the latch bolt by the strike the handle is held against movement by its spring 33, so that the bolt has free, easy, and relatively quiet movement, and the handle is at all times retained in its aligned normal position and is prevented from rattling. The latch bolt is retracted by rocking the handle either upwardly or downwardly, as shown in Fig. 6, one of the bosses 31, 32 acting as a fulcrum 60 65 cooperating with the casing, about which

the handle rocks, while the other boss presses upon its respective lug 42, 43 of the latch bolt. In case the bolt is not fully projected when engaged with the keeper, the handle will at all times be held against looseness and sagging by its spring 33. In the use of the strike, as shown, in which the latch bolt engaging portion is slightly inclined, the latch will be so mounted that its normal engaging position is such that it is not fully projected, so that any variations that may develop, due to warping of the door, or other causes, will be compensated for, and the latch will at all times function to tightly retain the door closed. Obviously, the latch, according to our invention, may be used upon either right or left hand doors.

We have illustrated and described a preferred and satisfactory embodiment of the invention, but it will be obvious that changes may be made therein, within the spirit and scope thereof, as defined in the appended claims.

Having thus described our invention, what we claim and desire to secure by Letters Patent is:

1. In a latch, a casing, a latch bolt slidably engaged in said casing, a handle member having spaced fulcrum means cooperating with said casing for independent rocking movement in one or the other directions, a spring in the casing engaging the latch bolt for normally projecting the same, a second spring in the casing engaging the handle member for normally maintaining the same against rocking movement, and means cooperating between said handle member and latch means for actuating the latter upon said rocking movement of the handle member in either direction.

2. In a latch, a casing having abutment portions, movable latch means carried by said casing, a handle member having spaced fulcrum points engaging said abutment portions of the casing for independent rocking movement in one or the other directions, means cooperating between said handle member and latch means for actuating the latter upon said rocking movement of the handle member in either direction, said latch means being free to have retracting movement independently of said handle member by re-tacting pressure directly applied thereto, and means adapted to position said handle member in its normal inoperative position independently of the position of the latch means.

3. In a latch, a casing, movable latch means carried by said casing, a handle member having spaced fulcrum means cooperating with said casing for independent rocking movement in one or the other directions, means cooperating between said handle member and latch means for actuating the latter upon said rocking movement of the handle member in either direction, and spring means

for yieldably retaining said handle member in its normal inoperative position independently of the position of the latch means.

4. In a latch, a casing, movable spring actuated means carried by said casing, a handle member having spaced fulcrum means cooperating with said casing for independent rocking movement in one or the other directions, means cooperating between said handle member and latch means for actuating the latter upon said rocking movement of the handle member in either direction, and spring means for yieldably retaining said handle member in its normal inoperative position independently of the position of the latch means.

5. In a latch, a casing, movable latch means carried by said casing, a handle member having spaced fulcrum means cooperating with said casing for independent rocking movement in one or the other directions, means cooperating between said handle member and latch means for actuating the latter upon said rocking movement of the handle in either direction, a spring carrying plate supported in said casing and engaged by said handle member, a spring secured at the under side of said plate and extended into relation with said handle member for yieldably retaining the same in its normal position independently of the position of said latch means.

6. In a latch, a casing, a flat sheet metal latch bolt slidably engaged in said casing, having transversely aligned projecting lug portions at each longitudinal edge, a spring in the casing engaging the latch bolt for normally urging the same outward, a handle member having spaced fulcrum means cooperating with said casing for independent rocking movement in one or the other directions, a second spring engaging the handle member to yieldingly hold said spaced fulcrum means against the casing, and abutment means carried by said handle member for engaging said respective lug portions of the latch bolt and respectively adapted to retract the latter upon said rocking movement of the handle member in either direction.

Signed at Bridgeport, county of Fairfield, and State of Connecticut, this 14th day of June, 1927.

RAYMOND G. MOORE.
ARTHUR CLAUD-MANTLE.
